[57] CLAIM

The ornamental design for a rear gauge mount and drive assembly for machine tools, as shown and described.

DESCRIPTION

FIG. 1 is a view of one side of a rear gauge mount and drive assembly for machine tools showing my new design.

FIG. 2 is a top plan view thereof.

FIG. 3 is a view of the side opposite that shown in FIG. 1.

FIG. 4 is a rear view.

FIG. 5 is a front view.

FIG. 6 is a bottom view but, as the bottom is not normally in view of the user, it is not considered a feature of the design.
